ATTORNEY

UNITED STATES PATENT OFFICE

129,637

DESIGN FOR A CARBURETOR FLOW TESTING CABINET

Alfred C. Korte, St. Louis, Mo.

Application May 13, 1941, Serial No. 100,918

Term of patent 14 years

To all whom it may concern:

Be it known that I, Alfred C. Korte, a citizen of the United States, residing at 4450 Bircher Blvd., in the city of St. Louis, State of Missouri, have invented a new, original, and ornamental Design for a Carburetor Flow Testing Cabinet, of which the following is a specification, reference being had to the accompanying drawing, forming part thereof.

The figure is a perspective view of a carburetor flow testing cabinet, showing my new design.

I claim:

The ornamental design for a carburetor flow testing cabinet, as shown.

ALFRED C. KORTE.
